UNITED STATES PATENT OFFICE.

CARL G. ANDERSON, OF BOSTON, MASSACHUSETTS, ASSIGNOR TO JOHN E. SWANSON, OF JAMAICA PLAIN, MASSACHUSETTS.

PROCESS FOR MAKING DIES.

Application filed December 26, 1919, Serial No. 347,506. Renewed July 28, 1923.

To all whom it may concern:

Be it known that I, CARL G. ANDERSON, a subject of the King of Sweden, and resident of Boston, county of Suffolk, State of Massachusetts, have invented an Improvement in Processes for Making Dies, of which the following description, in connection with the accompanying drawing, is a specification, like characters on the drawing representing like parts.

This invention relates to improvements in methods of forming dies and other articles, and the object thereof is to provide a novel and effective method of producing irregular shaped dies for cutting, and articles of similar character, which will enable the dies or articles to be made more rapidly and economically than in methods heretofore employed.

Broadly speaking the process comprises associating together upon a suitable base a series of units having substantially the cross section of the completed die, filling the interstices between said units with a material which will adhere to, or unite with, said units, and finishing the composite structure thus formed to produce a die or a pattern from which a die can be cast.

The method of making irregular cutting dies which has heretofore been practised is slow and expensive and requires unusual skill, and this is particularly true in respect to dies which are made for the purpose of cutting parts of shoes for which dies are required to be prepared for every size of every part of the shoe in order that the shoes may be made rapidly and economically. By reason of the number of different sizes of shoes and different styles of each size of shoe, a very large number of dies are required by a shoe factory, and the shape of the dies are changed from season to season for the varying styles. The expense, therefore, attendant upon the production of said dies is necessarily enormous and adds greatly to the overhead which must be charged against the finished product.

The present invention contemplates a production of a method which will not only greatly cheapen the manufacture of such

dies, but will enable them to be more rapidly produced.

In the usual method employed in the manufacture of dies, and particularly dies for cutting shoes, the shoe manufacturer furnishes to the die maker a paper pattern corresponding to the form of die which he desires for the part to be cut. From this pattern a sheet metal templet is made and from the templet a pattern is formed of sheet metal, such as tin, to correspond to the completed die. The die is thereafter forged from a strip of steel to correspond to the sheet metal pattern, the ends of the strip being welded together to form the completed die which is finished and ground to a cutting edge. In the manufacture of sole cutting dies, and other dies of large character, a composite strip of metal is used which comprises a section of steel for the cutting edge which is welded to a section of relatively soft iron which forms the major part of the die, the object being twofold; first to provide a die which will have a body portion of tough material able to withstand the repeated jars of the cutting machine, and second, to reduce the cost by using as small amount of expensive and high grade steel as is possible.

The welding together of the ends of such strips, in forming dies, requires unusual skill, by reason of the fact that the welding temperature of the steel and the iron differs and the steel if heated too highly very readily burns and produces a defective section in the die which readily breaks down.

By the present invention dies may be formed of cast iron which may be chilled or case-hardened, or they may be made of cast steel, and which will be much more economical in construction, and quite as effective and durable as the expensive dies heretofore constructed.

The preferred method is disclosed herein as employed in the manufacture of dies for cutting parts of shoes and consists in securing to a suitable base a series of units having a cross section corresponding to the cross section of the die, uniting the units

together to form an integral structure, detaching the die from the base and removing the means by which it was attached to it; then either using the die as a cutting die itself, or employing it as a moulding pattern in the casting of suitable metallic dies, preferably either of cast iron or of cast steel.

Preferred forms of units and the method by which they are associated to form a die, 10 or a die pattern, are illustrated in the accompanying drawings.

In the drawings:

Fig. 1 is a plan view of a block having secured thereto a series of associated units 15 to form a die adapted to cut the toe portion of the vamp of a shoe.

Fig. 2 is a detail plan view of a series of associated units secured to a base and extending along the straight and curved portion 20 of the templet, having the form of the desired piece to be cut.

Fig. 3 is a similar view showing the assembled units secured together and covered by a material which will adhere to, 25 or unite with, that of the units to bind the same to an integral structure and also to present a smooth outer surface for the die.

Fig. 4 is a side view of one of the units set in a block shown in section.

Fig. 5 is a similar view showing the unit covered with a coating.

Fig. 6 is a vertical cross sectional view through a sand mould having a cavity formed by a composite die which has been 35 removed from the mould.

Fig. 7 is a vertical sectional view through the die.

Fig. 8 is a vertical sectional view of the die after the same has been ground to a cutting edge.

The novel method comprising my invention consists broadly in applying to a suitable base, such as a block of wood 1, a series of units preferably of the same cross section and corresponding in cross section to that of the desired die. The units may be of any desired form such for example as that illustrated in Figs. 2, 3, 4 and 5, which comprises a slug 2, preferably of sheet metal, having curved, preferably arcuate, nesting faces 3 and 4, and provided at the bottom with one, or preferably a plurality of anchoring prongs 5 adapted to be imbedded in the base. The wooden block which forms the base preferably is a section of wood in which the grain extends vertically, so that the prongs are driven into the base in the direction of the length of the grain, thus enabling the slugs to be more easily and firmly secured to the base and without deflection which might occur if the same were driven into the wood transversely of the grain.

In forming the die a templet 6 which has been made corresponding to the form of the

desired article, such as a shoe pattern, is laid upon the block 1 and the slugs are driven along the edge of the templet so that their narrow edges abut against the templet and the transverse axis of the slug is substantially normal to the portion of the periphery against which it abuts. Where the slugs are associated in this manner along the straight edge of the templet they will lie closely together and form a practically continuous unbroken section, since the surfaces of adjacent slugs are in contact throughout their entire width. Where, however, the templets are associated together around a curved portion of the templet the inner edge portion of the slugs will abut, while a more or less of an interstice 7 will appear between the outer edge portions of the adjacent slugs, or if the adjacent curved faces of the slugs are placed closely together in following a gentle curve a more or less irregular or serrated surface 8 will be produced along the edge of the templet and a corresponding surface upon the outer edge of the die. In either event it is desirable that these interstices shall be filled in in the finished die.

When, therefore, the series of slugs have been secured to the base along the entire periphery of the pattern a suitable filling material 9 is applied which will fill these interstices and will unite the slugs together. Any suitable composition may be employed for this purpose which will unite to, or combine with the material of the slugs. Where the composite die thus made is to be used for a moulding pattern for casting integral dies, the interstices may be filled with shellac, plaster-of-Paris, or any other suitable adhesive material. Where the composite die is to be used as a cutting die itself the adjacent slugs desirably are united together by welding, brazing or soldering, so that the slugs, which preferably are of steel, will be united together to form an integral structure, the interstices preferably being so filled in that the finished die will present the same contour as one of the usual dies formed of a strip of steel bent to the proper shape.

When a die is thus formed it may be detached from the base and the prongs 5 milled, filed or ground off and the die used for cutting purposes in the usual manner. Dies thus made may also be employed as moulding patterns for casting dies of similar form in the usual well known manner. The composite die, however, may also be employed as a moulding die without removing the same from the base, by imbedding the die portion in the usual sand mould. The mould thus formed as illustrated in Fig. 6 in which the cavity 10 formed in a sand mould 11 is illustrated, the base and die from which the mould is made having

been removed. In the use of such a mould it is only necessary to cover the mould cavity with the usual flat covering having a sprue hole leading to the cavity through which the material may be introduced into it.

Where it is desired to form a die having straight sections or sections which are not abruptly curved different forms of units may be employed, for example, for a substantially straight portion of the die a unit 12 of wood, or of pliable material such as aluminum, lead or solder may be affixed to the base and such material may also be employed for sections of the die which do not comprise abrupt curves, thereby avoiding the necessity of using so many of the relatively narrow and thin slugs which are required to form the contour of sharp bends or angles. When it is desired, other forms of slugs may be used to conform to special requirements.

The units or slugs forming the composite die may be set by hand, but preferably will be set by suitable nailing machine having a magazine for feeding the slugs to the hammer and a guide adapted to follow the contour of the templet which corresponds to the pattern to be cut.

Where dies are to be cast from the composite die thus formed, the units will be set in the base at such predetermined distance from the edge of the templet as will allow for the contraction of the material in the mould.

It will be understood that any desirable form of unit or slug may be employed in the use of the process herein described and that the forms shown in the drawing are merely illustrative of the preferred form of slug which is now best known to me. It will also be understood that various other modifications in the steps of the method may be made within the spirit and scope of the following claims.

Having thus described my invention, what I claim as new and desire to secure by Letters Patent, is:

1. Steps in the method of forming a die which consist in affixing to a base a series of associated units each having a cross section corresponding substantially to that of the completed die and binding said units together by material substantially homogeneous with that of said units to form an integral structure and using the assembled structure as a moulding pattern and casting a die from the mould formed thereby.

2. Steps in the method of forming a die which consist in affixing to a base a series of associated units each having a cross section corresponding substantially to that of the completed die, uniting with said associated units by a material which will unite with that of the units to fill the interstices

between said units and produce an integral structure and finishing said structure to the required form of the die, using the assembled structure as a moulding pattern and casting a die from the mould formed thereby.

3. Steps in the method of forming a die which consist in affixing to a base a series of associated units each having a cross section corresponding substantially to that of the completed die, uniting together the adjacent units to form an integral structure, detaching the same from the base, removing the means by which said units were affixed to the base and finishing the structure to the required form of the die, using the assembled structure as a moulding pattern and casting a die from the mould formed thereby.

4. A method of forming a die which comprises affixing to a base a series of associated units each having a cross section corresponding substantially to that of the completed die, applying to the associated units a material which will adhere to, or unite with, the material of said units to fill the interstices therebetween and produce a finished outer surface using the die thus formed as a moulding pattern and casting a die from the mould.

5. A method of forming a die which comprises affixing to a base a series of associated units each having a cross section corresponding substantially to that of the completed die, uniting together the adjacent units to form an integral structure, detaching the same from the base, removing the means by which said units were affixed to the base and finishing the die structure, using the die thus formed as a moulding pattern and casting the die from the mould thus formed.

6. A method of forming a die which consists in affixing to a wooden base a series of closely juxtaposed sheet metal slugs having anchoring prongs and having a cross section corresponding substantially to that of the die, uniting said slugs together to form an integral metallic structure and finishing the die to conform to the desired shape and using the finished structure as a moulding pattern and casting a die from the mould formed thereby.

7. A method of forming a die which consists in affixing to a wooden base a series of closely juxtaposed sheet metal slugs having anchoring prongs and having a cross section corresponding substantially to that of the die, uniting said slugs together to form an integral metallic structure, detaching the die from the wooden base, removing the prongs and finishing the die to the desired shape and using the finished structure as a moulding pattern and casting a die from the mould formed thereby.

8. A method of forming a die which consists in affixing to a wooden base a series of closely juxtaposed sheet metal slugs having anchoring prongs and having a cross section corresponding substantially to that of the die, uniting said slugs together to form an integral metallic structure and finishing

the die to conform to the desired shape, using the finished die as a moulding pattern and casting a die from the mould formed thereby.

In testimony whereof, I have signed my name to this specification.

CARL G. ANDERSON.
